UNITED STATES PATENT OFFICE.

AUGUST DENKER, OF RATH, NEAR DUSSELDORF, GERMANY, ASSIGNOR TO RUDOLF DIETEL, OF DUSSELDORF-OBERCASSEL, GERMANY.

MACHINE FOR CUTTING THE TEETH OF SPUR-WHEELS.

1,115,909.

Specification of Letters Patent.

Patented Nov. 3, 1914.

Application filed May 6, 1910. Serial No. 559,676.

To all whom it may concern:

Be it known that I, AUGUST DENKER, a subject of the German Emperor, and residing at No. 9 Wahlenstrasse, Rath, near 5 Dusseldorf, Germany, have invented certain new and useful Improvements in Machines for Cutting the Teeth of Spur-Wheels, of which the following is a specification.

This invention has for its object to provide 10 an improved machine for forming spur wheels with involute teeth by cutting a wheel blank fixed on a worktable that is capable of being fed across the bed of a machine and also of being rotated on its own 15 axis opposite a reciprocating cutting tool.

This invention is applicable to machines 20 of the type in which the wheel blank can be given a combined rotation and cross feed of such a kind that a tooth space will be finished before the wheel blank is rotated through a distance equal to the pitch of the teeth to be cut.

The improvements consist in connecting 25 the gearing that rotates the worktable with the cross feed gearing by means of a clutch which on being disconnected, allows the gearing that rotates the worktable to serve also to rotate the worktable through a distance equal to the pitch of the teeth to be 30 cut. The speed ratio of the cross feed gearing, and the speed ratio of the gearing for rotating the worktable may be varied either each alone or both to suit the number of teeth, or their pitch or both, by changing 35 the wheels of the corresponding gearings.

In the accompanying drawings which illustrate by way of example one form of the present invention, Figure 1 is a side elevation of the improved machine, in which 40 only those parts are shown which are necessary for understanding the invention. Fig. 2 is a partial horizontal section of the machine with the wheel blank removed. Fig. 3 is a diagrammatic plan showing the position of the tool about to make the first cut in a solid wheel blank. Fig. 4 is a diagrammatic plan showing the position of the tool when the first tooth has been cut; and Fig. 45 5 is a sectional view of the whole gearing extended in line (that is, not projected).

The improved machine in the form shown has the general arrangement of a vertical slotting machine. The horizontal worktable is mounted on the bed of the 55 machine and is capable of being fed along and also across the bed, and of being rotated on its own vertical axis. The means for feeding the table along the bed are not shown, because they have no essential relation to the subject matter of the present invention.

c is a shaft mounted on one side of the machine framing, and from which the cross feed and the rotation of the worktable are 65 derived.

b is a pawl actuated at each stroke of the tool ram by means of a connecting rod from the driving shaft of the machine for operating a ratchet wheel *a* that is fixed on the shaft *c*, whereby the shaft *c* is rotated intermittently at the end of each stroke of the tool. The rotation of the shaft *c* is transmitted through bevel wheels *d* to a shaft *e* and thence through intermediate gears of variable speed ratio to a cross feed 70 screw *i*. The worktable receives its cross feed through a nut formed on it engaging the cross feed screw *i*. The rotation of the shaft *e* is also transmitted through a toothed wheel *f* to a toothed wheel *g* which is loose 75 on a pin *h* fixed in the framing of the machine. The wheel *g* carries one-half of a clutch *m* whose other half is capable of rotating with and of sliding along the said pin *h*. This pin is connected with a worm 80 shaft *l* through suitable gearing *n* having a variable speed ratio; and the coacting faces of the clutch are so constructed that they will be brought into engagement with each other only when in a predetermined position. This engagement is preferably effected 85 automatically, for example, by means of a suitable spring *x* bearing against the clutch.

The speed ratios of the gearing between 90 the shaft *e* and the cross feed screw *i* and of that between the clutch *m* and the worm shaft *k* *l*, may be varied by changing a pair of toothed wheels mounted on one of the shafts. The worm *k* engages a worm 100

wheel connected to the worktable and thereby imparts rotary motion to the latter.

In order to cut involute teeth, the cross feed and rotary feed of the worktable must have a relation to the tool such as to impart to the wheel blank to be cut, a motion equivalent to the rolling motion of a toothed wheel having the same pitch circle along a rack. For this purpose the speed ratios of the gearing producing the cross feed and rotary feed of the table must be such that the ratio of the speed of revolution of the cross feed screw i to the speed of revolution of the shaft e must be equal to the ratio of the pitch of the wheel to be cut to the pitch of the driving worm wheel connected to the worktable. Further, the ratio of the speed of revolution of the clutch m to the speed of revolution of the worm k must be equal to the ratio of the number of teeth of the wheel to be cut to the number of teeth of the driving worm wheel. Also, the speed of revolution of the wheel f must have a ratio to the speed of revolution of the wheel g which is inverse to that of the pitch of the cross feed screw i to the pitch of the worm k so as to compensate for the difference between these last two pitches. Consequently the product obtained by multiplying the speed ratio of the gearing between the cross feed screw i and shaft e by the speed ratio of the gearing between the clutch m and worm k will be the speed ratio of the cross feed of the table to the peripheral velocity of the worm wheel. Now since the product of the multiplication is the ratio of the diameter of the pitch circle of the wheel to be cut to the diameter of the pitch circle of the driving worm wheel, the consequence is that the speed of the cross feed of the wheel blank to be cut is equal to the speed of revolution at the pitch circle, that is to say, the motion of the wheel blank is the same as the rolling motion of a toothed wheel having a pitch circle of equal diameter along a rack. If, for example the worm wheel on the worktable has 140 teeth with a pitch of 5π millimeters, that is a pitch circle diameter of 700 millimeters, and if it is desired to cut a wheel with 100 teeth of a pitch of 12π millimeters, that is a pitch circle diameter of 1200 millimeters, then the ratio of the speed of revolution of the cross feed screw i to the speed of revolution of the shaft e must be as 12 to 5, and the ratio of the speed of revolution of the clutch m to the speed of revolution of the worm k , must be as 100 to 140. The product of multiplication of these two ratios is

$$60 \quad \frac{12}{5} \times \frac{100}{140} = \frac{1200}{700},$$

and the ratio of 1200 to 700 will be the ratio of the speed of the cross feed of the worktable to the peripheral speed of the worm

wheel at the pitch circle. Now since the ratio of the pitch circle diameter of the wheel to be cut, to the pitch circle diameter of the worm wheel is likewise as 1200 to 700, it is clear that the ratio of the peripheral speed of the wheel to be cut to the peripheral speed of the worm wheel, will likewise be as 1200 to 700; that is to say, the peripheral speed at the pitch circle of the wheel to be cut, is equal to the amount of cross feed of the worktable.

The operation of the improved machine is as follows:—The wheel blank to be cut having been fixed on the worktable and brought into the position shown in Fig. 3 relatively to the cutting tool, the machine is started. During the up and down movement of the cutting tool, the wheel blank receives a cross feed and is simultaneously rotated on its own axis until it assumes the position shown in Fig. 4 relatively to the cutting tool, which is thus caused to cut a tooth space in the wheel blank. The wheel blank is then moved back into its initial position by means of hand cranks placed on the end of the shaft l or the cross feed screw i , after which the parts of the clutch m are disconnected, and the shaft l is rotated independently of the spindle i , until after the rotating part of the clutch part has made a complete revolution whereupon the clutch m is automatically connected again. Since the speed ratio of the clutch m to the work k l corresponds to the number of teeth of the driving worm wheel, therefore after the clutch part has made a complete revolution, the wheel blank will have been rotated through an angle corresponding to the pitch of the wheel to be cut, that is in the example under consideration, through an angle of 3 degrees 36 minutes, which corresponds to a pitch of 12. If it is desired to cut toothed wheels having a different pitch or a different number of teeth, it will be necessary to change merely one pair of toothed wheels of the gearing between the shaft e and the screw i or one pair of toothed wheels of the gearing between the clutch m and the worm shaft k l . When both the pitch and the number of teeth are different, one pair of toothed wheels will have to be changed in both gearings.

The improved machine is very much simpler to construct and manipulate than the existing shaping or slotting machines for cutting wheel teeth, and the present improvements are easily applicable to every existing shaping or slotting machine.

Having now described my invention what I claim as new and desire to secure by Letters Patent is:—

1. In a machine for cutting teeth of spur gear wheels, the combination of a reciprocating cutting tool, a suitable support for the wheel blank to be cut, means to effect

- between said blank and said tool an advance and return motion equivalent to the rolling motion of a toothed wheel, of the same pitch diameter, along a rack whereby 5 a single complete tooth space will be cut by said tool, and the blank restored to its initial position relatively to the cutting tool, and means included in said first named means whereby said blank may be indexed.
- 10 2. In a machine for cutting teeth of spur gear wheels, the combination of a reciprocating cutting tool, a suitable support for the wheel blank to be cut, means to impart thereto a cross-feed, and means to simultaneously 15 impart thereto rotation on its own axis, the resultant motion imparted to the blank relatively to the cutting tool being equivalent to the rolling motion of a toothed wheel, of the same pitch diameter, along 20 a rack whereby a complete tooth space will be cut by said tool, and means included in said last named means whereby said blank may be indexed.
3. In a machine for cutting teeth of spur gear wheels, the combination of a reciprocating cutting tool, a suitable support for the wheel blank to be cut, means to impart thereto a cross-feed, means to simultaneously 25 impart thereto rotation on its own axis, and disengaging means to normally connect said cross-feed means with said means to impart rotation to the wheel blank.
4. In a machine for cutting teeth of spur gear wheels, the combination of a reciprocating cutting tool, a suitable support for the wheel blank to be cut, gearing to effect 30 between said blank and said tool an advance and return motion equivalent to the rolling motion of a toothed wheel, of the same pitch diameter, along a rack, whereby 35 a single complete tooth space will be cut by said tool and the blank restored to its initial position relatively to the cutting tool, and means included in said gearing 40 whereby a portion thereof may be rendered temporarily inoperative and the said wheel blank indexed through the continuously operative portion of said gearing.
5. In a machine for cutting teeth of spur gear wheels, the combination of a reciprocating cutting tool, a suitable support for the wheel blank to be cut, means to impart thereto a cross-feed, means to simultaneously 45 impart thereto rotation on its own axis, a clutch normally connecting said cross-feed means with said means to impart rotation to the wheel blank and adapted to be disengaged, and means to automatically connect said clutch when the same has made 50 a complete revolution.
6. In a machine for cutting teeth of spur gear wheels, the combination of a reciprocating cutting tool, a suitable support for the wheel blank, gearing for imparting thereto a cross-feed, gearing for rotating 55
- said support on its own axis, a clutch for connecting the cross-feed gearing and said rotating gearing and adapted to be disengaged, and means whereby the rotating gearing may be actuated to rotate the support on its axis and through the angular amount of the pitch of the teeth to be cut. 70
7. In a machine for cutting teeth of spur gear wheels, the combination of a reciprocating cutting tool, a suitable support for the wheel blank, gearing for imparting thereto a cross-feed and including a pair of change wheels, gearing for imparting rotation to said support on its axis and including a pair of change wheels, and a clutch for connecting the cross-feed gearing with the rotating gearing. 75
8. In a machine for cutting teeth of spur gear wheels, the combination of a reciprocating cutting tool, a suitable support for the wheel blank to be cut, a feed-screw to impart a cross-feed motion to said support, a worm wheel and worm shaft to rotate the support, and intermediate connecting gearing whose combined velocity ratio is equal to the ratio of the pitch circle diameter of the wheel to be cut to the pitch circle diameter of the worm wheel multiplied by the ratio of the pitch of the worm wheel to the pitch of the cross-feed screw; change gearing for effecting the cross-feed and having a velocity ratio equal to the pitch of the worm wheel to the pitch of the wheel to be cut; change gearing for effecting the rotation of the wheel blank 85
9. In a machine for cutting teeth of spur gear wheels, the combination of a reciprocating cutting tool, a suitable support for the wheel blank to be cut, a feed screw to impart a cross-feed motion to said support, a worm wheel and worm shaft to rotate the support, and intermediate connecting 90
- gearing whose combined velocity ratio is equal to the ratio of the pitch circle diameter of the wheel to be cut to the pitch circle diameter of the worm wheel multiplied by the ratio of the pitch of the worm wheel to the pitch of the cross-feed screw; change gearing for effecting the cross-feed and having a velocity ratio equal to the pitch of the worm wheel to the pitch of the wheel to be cut; change gearing for effecting the rotation of the wheel blank 95
10. In a machine for cutting teeth of spur gear wheels, the combination of a reciprocating cutting tool, a suitable support for the wheel blank to be cut, a feed screw to impart a cross-feed motion to said support, a worm wheel and worm shaft to rotate the support, and intermediate connecting 100
- gearing whose combined velocity ratio is equal to the number of teeth of the wheel to be cut to the number of teeth of the worm wheel; and a fixed gearing connecting said two sets of change gearing and having a 105 velocity ratio equal to the ratio of the pitch of the worm wheel to the pitch of the feed screw.
11. In a machine for cutting teeth of spur gear wheels, the combination of a reciprocating cutting tool, a suitable support for the wheel blank to be cut, a feed screw to impart a cross-feed motion to said support, a worm wheel and worm shaft to rotate the support, and intermediate connecting 110
- gearing whose combined velocity ratio is equal to the ratio of the pitch circle diameter of the wheel to be cut to the pitch circle diameter of the worm wheel multiplied by the ratio of the pitch of the worm wheel to the pitch of the cross-feed screw; change gearing for effecting the cross-feed and having a velocity ratio equal to the pitch of the worm wheel to the pitch of the wheel to be cut; change gearing for effecting the rotation of the wheel blank 115
12. In a machine for cutting teeth of spur gear wheels, the combination of a reciprocating cutting tool, a suitable support for the wheel blank to be cut, a feed screw to impart a cross-feed motion to said support, a worm wheel and worm shaft to rotate the support, and intermediate connecting 120
- gearing whose combined velocity ratio is equal to the ratio of the pitch circle diameter of the wheel to be cut to the pitch circle diameter of the worm wheel multiplied by the ratio of the pitch of the worm wheel to the pitch of the cross-feed screw; change gearing for effecting the cross-feed and having a velocity ratio equal to the pitch of the worm wheel to the pitch of the wheel to be cut; change gearing for effecting the rotation of the wheel blank 125
13. In a machine for cutting teeth of spur gear wheels, the combination of a reciprocating cutting tool, a suitable support for the wheel blank, gearing for imparting thereto a cross-feed, gearing for rotating 130

and having a velocity ratio equal to the ratio of the pitch of the worm wheel to the pitch of the feed screw; and disengaging means between said fixed gearing and said change gearing for rotating the support.

In testimony whereof I have signed my

name to this specification in the presence of two subscribing witnesses.

AUGUST DENKER.
